UNITED STATES PATENT OFFICE.

EMILE CEASAR GENEUX, OF JEANERETTE, LOUISIANA.

LANTERN-HOLDER.

SPECIFICATION forming part of Letters Patent No. 344,649, dated June 29, 1886.

Application filed August 17, 1885. Serial No. 174,543. (No model.)

To all whom it may concern:

Be it known that I, EMILE CEASAR GENEUX, of Jeanerette, Iberia parish, Louisiana, have invented an Improvement in Lanterna Holders, of which the following is a specification.

The special object of the invention is to provide the lantern with a spring attachment constructed and adapted to be used, as herein-after described, with vehicles.

10 Figure 1 of the drawings is a perspective view of a lantern with my invention applied thereto. Fig. 2 is a detail view, in sectional elevation, of my device on a buggy-arm. Fig. 3 is a vertical cross-section of my lantern attachment.

15 In the drawings, A represents my handle or spring attachment, which is soldered to the back of lantern and just above the middle thereof, so that the lantern may be conveniently used with vehicles, as well as by hand.

20 B is the arm of a buggy or other vehicle provided with an arm-socket, b, of irregular or non-circular form on the inside. Corresponding to and fitting into this I make the hollow post a, having the outer collar, a', to rest upon the top of socket b.

25 C is an endless wire, or it may be the two

ends of a wire passed through the hollow post a, and soldered or otherwise fastened thereto. Above said post the wire is bent to form the 30 coil-springs c c, then carried down and bent at right angles to make the bow c', which springs under the box or post a. The bars c² c², which are preferably parallel, are soldered to the lantern, as shown in Fig. 1 of the drawings. 35

By connecting the lantern with a vehicle by my spring attachment it is not so liable by jars or joits to be displaced or broken, while the lantern may be readily detached for use 40 about the stable or elsewhere.

Having thus described all that is necessary to a full understanding of my invention, what I claim is—

45 The spring attachment A, for connecting a lantern with a vehicle, consisting of the box or post a, having outer collar, a', and the wire C, fastened therein, said wire being bent to form coil-springs c c, bow c', and bars c² c², substantially as shown and described.

EMILE CEASAR GENEUX.
